UNITED STATES PATENT OFFICE.

JAMES FOLEY, OF BROOKLYN, NEW YORK.

BASIN COCK AND OVERFLOW.

SPECIFICATION forming part of Letters Patent No. 267,863, dated November 21, 1882.

Application filed September 12, 1882. (No model.)

To all whom it may concern:

Be it known that I, JAMES FOLEY, of Brooklyn, in the county of Kings and State of New York, have invented an Improvement 5 in Basin Cocks and Overflows, of which the following is a specification.

In my Patent No. 6,739 (reissue) there is a stand-pipe that connects with the sewer or waste pipe and with an arm to the escape-pipe 10 of the basin, and within this stand-pipe there is a tubular valve that is raised or lowered by a stem to open or close the waste-pipe. The handle for the stem comes above the slab at the side of the basin. In some 15 instances persons do not know how to operate the valve to allow the water to escape, and in other instances the seat of the valve becomes obstructed by sediment and foreign substances.

20 My present invention is for overcoming the aforesaid difficulties by combining with the stand-pipe and overflow a tubular plug at the lower end of the overflow-pipe, which plug forms a cock at the junction of the branch to 25 the basin with the stand-pipe, and to this overflow-pipe a stem and handle are applied, so as to turn the same, and a spring presses the plug into the barrel of the cock.

In the drawings, Figure 1 is a vertical section 30 of my improved overflow and basin cock, and Fig. 2 is a sectional plan at the line *x x*.

The stand-pipe *a* is provided with a screw-cap, *b*, at the top, which cap is adapted to set upon the surface of the marble slab *d*, and to 35 support the stand-pipe. This stand-pipe, however, may be firmly secured to the slab by screw-rings on its exterior surface, or otherwise, so as to be held in place independently of the screw-cap *b*. At the lower end of this 40 stand-pipe there is a vertical conical barrel, *e*, from which there is a lateral connection, *f*. The lower end of *e* is to be connected to the waste-pipe *g* by solder or a screw-coupling, and the lateral connection *f* is connected by a 45 pipe, *h*, to the escape-opening at the bottom of the basin *l*, and there is a water-way at *m* opening from the stand-pipe *a* into the lateral pipe *f*, so that water from the basin can always run freely into the stand-pipe.

Within the barrel *e* there is a tubular plug, 50 *o*, forming a cock. It may be ground in or otherwise made water-tight, and said plug is open at the lower end, and there is a lateral opening through the plug corresponding to the tube *f*, so that when this plug *o* is turned to 55 make the holes correspond the water flows away freely from the basin; but when the lateral opening *f* is closed by turning the plug *o* the water cannot escape, but will accumulate both in the basin and in the stand-pipe until 60 it rises as high as the top of the tubular overflow *s*, that is formed as a tubular extension of the plug *o*, or as a separate tube soldered into the same.

At the top of the overflow-tube *s* there is a 65 stem, *r*, with branches at its lower end connected permanently with *s*, and the stem passes up through the cap *b* and terminates with a handle, *t*, by means of which the overflow and plug can be rotated to open or close the basin-cock *o*, and the spring *v* around the stem *r* serves to press the plug into its barrel and keep the basin-cock tight.

By the removal of the screw-cap the overflow and cock can be taken out for cleaning.

This improvement is available for a bath-tub as well as a wash-basin, the overflow-pipe being elongated and the stand-pipe being of a size adapted to be placed at one end or side of the bath-tub.

I claim as my invention—

The combination, with the stand-pipe, waste-pipe, and lateral connection to the basin or bath, of the cock at the junction of the respective pipes, having a tubular plug, an overflow-pipe, which is a continuation of the tubular plug, the stem and handle by means of which the plug is turned, and the cap at the upper end of the stand-pipe, substantially as set forth.

Signed by me this 5th day of September, 90
A. D. 1882.

JAMES FOLEY.
